MEASURED DOSE DISPENSING CONTAINER OR THE LIKE

Katsuhiko Wakamatsu, 5-go, 10-ban, 2-chome, Momoi,
Tokyo-to, Japan

Filed June 18, 1969, Ser. No. 17,757

Claims priority, application Japan Dec. 24, 1968

Term of patent 14 years

Int. Cl. D9—04

U.S. Cl. D9—207

FIG. 3

FIG. 1

FIG. 2

FIG. 4

FIG. 1 is a front perspective view of a measured dose dispensing container or the like, showing my new design;

FIG. 2 is a rear perspective view thereof;

FIG. 3 is a top plan view thereof; and

FIG. 4 is a cross-sectional view taken on line IV—IV of FIG. 3.

I claim:

The ornamental design for a measured dose dispensing container or the like, substantially as shown.
